(57) **CLAIM**

The ornamental design for a cartridge substantially as shown and described.

DESCRIPTION

FIG. 1 is a front and left side perspective view of a first embodiment of a cartridge showing my new design.

FIG. 2 is a front view of the cartridge of FIG. 1.

FIG. 3 is a rear view of the view of the cartridge of FIG. 1.

FIG. 4 is a left side view of the cartridge of FIG. 1.

FIG. 5 is a right side view of the cartridge of FIG. 1.

FIG. 6 is a top view of the cartridge of FIG. 1.

FIG. 7 is a bottom view of the cartridge of FIG. 1.

FIG. 8 is a top view of a second embodiment of a cartridge showing my new design; and,

FIG. 9 is a top view of a third embodiment of a cartridge showing my new design.

The broken lines in FIGS. 8 and 9 depict portions of the cartridge that form no part of the claimed design.

1 Claim, 5 Drawing Sheets
